UNITED STATES PATENT OFFICE.

HARRY E. VEGIARD, OF ROCHESTER, NEW YORK.

SAILING GAME.

Application filed February 12, 1923. Serial No. 618,708.

To all whom it may concern:

Be it known that I, HARRY E. VEGIARD, a citizen of the United States, residing at Rochester, in the county of Monroe and 5 State of New York, have invented certain new and useful Improvements in Sailing Games, of which the following is a specification.

The object of this invention is to provide 10 a new and improved form of game which game will involve the navigation of toys representing boats on a chart representing a sailing course, the navigation of the toys following the practice of navigating boats 15 in sailing a race over a marked course, and also involving the rules that must be followed in sailing such a race.

Sail boat races are usually held over a fixed course, the important points of which 20 are marked by buoys or turning stakes. The rules require that the vessels shall sail to and around the stake and in doing so they must go with or against or across the wind as the circumstances may require and avoid 25 other vessels that are sailing the course in the same race as the rules may require.

My game involves, by analogy at least, and as far as possible in practice, the conditions and the rules of sailing such a race. 30 For this purpose I have provided a drawing in which—

Figure 1 shows a game board having a triangular course marked thereon.

Figure 2 shows an instrument having a 35 dial and pointer which is used by the players for determining the length of their respective moves, etc.

Figure 3 shows a marker representing a sailing vessel.

40 Figure 4 shows a marker representing a buoy.

In the drawing, like reference numerals indicate like parts.

The game may be played by any number 45 of players preferably from one to ten, each of the players being provided with a marker representing a sail boat. These boats are to be moved over the triangular course shown on the game board (laid out on 50 imaginary water). The course is marked at each corner by buoys or markers such as are shown in Figure 4. One buoy at the starting point is known as the west buoy and is indicated by reference numeral 1, and 55 another buoy at the east end of the course is known as the east buoy and is indicated

by the reference numeral 2 and the third buoy is placed at the upper corner and is known as the north buoy and is indicated by the reference numeral 3. 60

The course is laid out with a choice of one or more different runs to the east buoy against an imaginary east wind, and is, therefore, known as a beat to windward. It is well known that a boat cannot sail directly into the wind and, therefore, this course must be laid so that the boat will travel across the wind so as to make headway from the west buoy to the east buoy. For this purpose the course is marked so 65 that the boat can sail across the wind first by sailing to the left of the direct line with the east wind off the starboard quarter (right side of the boat) to the positions 8, 8 and then sailing to the right to the second 70 buoy with the wind off the port side of the boat (left side of the boat) or the boat may be sailed to the right of the direct course to the positions 9, 9 and then to the left to the positions 8, 8 and then to the right again to 75 the east buoy 2. On the drawing five parallel lines of colored circles are shown in four different arrangements each of the lines preferably having circles of a different color. The colors preferably used are red, 80 brown, green blue, and black. At another part of the board five converging lines are shown and at still another part of the board two sets of converging lines are shown. In all, six sets of lines are shown. A starting 85 line 4 is shown with five starting positions in line with each other from each of which positions a line of circles runs to the left of the direct course and a line of circles runs to the right of the direct course. The outer 90 end of each of these lines is connected by a third line of circles and from the farthest junction point of the two lines of one color extends another line of circles of the same color to the turning buoy 2. In this last 95 named set five converging lines are pictured each of a different color each line forming a continuation of the lines of the same color above mentioned. The distance between any two consecutive circles represents a knot. 100 From the second buoy to the third buoy three converging lines of colored circles are shown and from the third buoy back to the finish line five lines of colored circles are shown. 105

110 Each sail boat is moved in turn a variable distance and for the purpose of determining

the distance and direction in which each boat is moved I provide an instrument 5 having a dial 6 and a pointer 7 mounted to rotate over the dial. The dial is marked 5 with the eight cardinal points and is divided into segments of forty-five degrees each in which segments are marked characters indicating 1, 2, 3 or 4 knots, the characters "1 knot" occurring four times on the dial, 10 the characters "2 knots" occurring twice on the dial, and the characters "3 knots" and "4 knots" being marked once each on the dial.

Each player is allowed to spin the pointer in turn and when the pointer comes to rest 15 it points to one or the other segments and the characters therein indicate the distance in knots which he is allowed to move his vessel. If the pointer stops on the line between the adjacent segments it stops 20 "in irons" and puts the vessel "in irons" so that it cannot go forward and is unmanageable, and must, therefore, remain stationary or drift back.

To play the game, each person participating 25 draws a card which has a number thereon representing the number on the sail boat belonging to the player and the turn in which the player moves from the starting line. Each person is then furnished with a 30 marker representing the sail boat with his particular number thereon. The person having boat No. 1 spins the pointer and moves his boat in accordance with the indication when the pointer comes to rest. If 35 the pointer stops at 2 knots the boat is moved forward by two circles from its position either on or behind the starting line. The player can start on any line of circles at the starting point and move forward in 40 straight lines or diagonally cross lines as long as the move takes him away from the starting lines. From the starting line the boats can take the course to the left to the positions 8, 8 or they can take the course to 45 the right to the positions 9, 9 whichever is the more advantageous, and having reached the positions 9, 9 they can then sail the course to the positions 8, 8. In making each move forward the boat can move 50 straight along a line or across from one line to another or diagonally across lines as long as the move takes him farther away from the starting line and out of the way of another boat.

55 The boat may have its forward progress interfered with in several ways as follows:

Certain circles are marked with a gold star 10 which indicate calm and if the last move lands the boat on that circle the boat 60 drifts back to the next circle 11 marked

with a silver star because of the calm. For this purpose the stars are always arranged in pairs.

The progress of a boat can always be interfered with by the position of another boat. 65 It is always assumed that the wind is blowing from a certain direction usually from the east and if the boat at the end of its move lands in a position that is to the windward of a boat ahead the previous boat 70 necessarily takes the wind from the sails of the following boat if the boat is traveling in the same direction on the next parallel line and the following boat therefore is unable to pass the leading boat until the leading boat 75 moves or takes another tack. The following boat can move across lines diagonally if it will enable him to cross his opponent's line in the rear of the opponent and land on a line ahead which is to windward, thereby 80 getting the windward position. This is known as splitting tacks and will take the wind from the sails of the boat that was previously ahead.

If a boat is on the turning buoy no boat 85 can pass until the boat has left the circle at the turning buoy. Otherwise the boats would foul and this will eliminate the player causing the foul from the game. In this way the boats can progress around the course 90 and the boat reaching the finish line the first will win the game.

I claim:

1. A sailing game comprising a chart of a triangular sailing course in combination 95 with figures representing boats, said triangular course being pivoted into sections, each of said sections comprising a series of individual sailing courses terminating into a single turning point at the end of each 100 section, a counter for determining successive positions of the boats on the individual sailing courses.

2. A sailing game comprising a chart of a triangular sailing course in combination 105 with figures representing boats, said triangular course being pivoted into sections, each of said sections comprising a series of individual sailing courses terminating into a single turning point at the end of each 110 section, a counter for determining successive positions of the boats on the individual sailing courses, connecting lines between the individual sailing courses to allow the boats to drift from one of the individual sailing courses to the other at predetermined points on the triangular sailing course.

In testimony whereof I affix my signature.

HARRY E. VEGIARD.
